DESIGN FOR A SINK CABINET

Charles H. Widman, Detroit, Mich., assignor to
The Murray Corporation of America, Detroit,
Mich., a corporation of Delaware

Application November 26, 1934, Serial No. 54,158

Term of patent 14 years

To all whom it may concern:

Be it known that I, Charles H. Widman, a citizen of the United States, residing in Detroit, in the County of Wayne, State of Michigan, have invented a new, original, and Ornamental Design for a Sink Cabinet, of which the following is a specification, reference being had to the accompanying drawing, forming a part thereof, wherein:

Figure 1 is a front, perspective view of the sink cabinets showing my new design, and

Fig. 2 is a side view of the cabinet illustrated in Fig. 1.

The dominant features of the cabinet consist of the sliding doors for enclosing the cabinet compartments and the drawers on the sides of the ventilating panel.

I claim:

The ornamental design for a sink cabinet substantially as shown and described.

CHARLES H. WIDMAN.
